UNITED STATES PATENT OFFICE.

RICHARD VOIT, OF PHILADELPHIA, PENNSYLVANIA.

DESIGN FOR A BEDSPREAD OR SIMILAR ARTICLE.

Application filed November 23, 1923. Serial No. 7,863. Term of patent 14 years.

To all whom it may concern:

Be it known that I, RICHARD VOIT, a citizen of the United States, residing at Philadelphia, in the county of Philadelphia and State of Pennsylvania, have invented a new, original, and ornamental Design for a Bedspread or Similar Article, of which the following is a specification, reference being had to the accompanying drawing, forming part thereof.

The figure is a plan view of a section of a bedspread or similar article, showing my new design.

The complete bedspread is a repeat of the portion illustrated on the drawing.

I claim:

The ornamental design for a bedspread or similar article as shown.

RICHARD VOIT.
